A. M. S.

UNITED STATES PATENT OFFICE.

JAMES H. PAPPAS, OF SAN FRANCISCO, CALIFORNIA, ASSIGNOR OF ONE-HALF TO
JOHN BOYAJIAN, OF SAN FRANCISCO, CALIFORNIA.

AMUSEMENT APPARATUS.

Application filed September 18, 1922. Serial No. 588,924.

To all whom it may concern:

Be it known that I, JAMES H. PAPPAS, a subject of the King of Greece, residing at San Francisco, in the county of San Francisco and State of California, have invented new and useful Improvements in Amusement Apparatus, of which the following is a specification.

The present invention relates to novel amusement apparatus which is capable of a variety of effective uses in connection with places of amusement or as an amusement device itself, the principal object being to provide an apparatus through the use of which, persons may be paired, each couple without the knowledge of the identity of one another until the pairing has been effected.

An object of the invention is to provide apparatus of the character described which may be used as an entranceway for places of amusement such as dance halls or the like, the arrangement being such that persons using the entranceway must pass on opposite sides of a screen or partition, which will prevent persons on one side from seeing persons on the other side, there being suitable means operatively associated with the partition in such manner that said persons may obtain partners without the knowledge of the identity of the partner, thus making it possible to prevent said persons from changing partners.

The invention further takes into consideration the pairing off of couples in the manner desired, through the medium of flexible tie members, which members may be employed to secure or to lock the persons of each couple together, thereby preventing the changing of partners.

The invention also includes a novel amusement system or method of pairing persons for participation in various forms of amusement without permitting the persons to select partners of their own choosing, thus causing an element of chance to enter into the selection of partners and providing a highly amusing procedure which will provoke many funny and ludicrous situations.

The invention possesses other advantages and features some of which, with the foregoing will be set forth at length in the following description where I shall outline in full that form of the invention which I

have selected for illustration in the drawings accompanying and forming a part of the present specification. In said drawings I have shown certain forms of the construction of my invention, but it is to be understood that I do not limit myself to such forms since the invention as expressed in the claims may be embodied in a plurality of forms.

Referring to the drawings:

Fig. 1 represents a semi-diagrammatic view in top plan in a place of amusement such as a dance hall, showing one way of employing the apparatus of my invention.

Fig. 2 is a perspective view of a part of the apparatus of the invention.

Fig. 3 is a side elevation of a part of the apparatus of the invention, a moving platform or floor being incorporated therewith, the floor proper being shown in section.

Fig. 4 represents a vertical sectional view of the device of the invention showing a couple as appearing when paired, and the conveyor or floor incorporated with the apparatus.

In the accompanying drawings in Fig. 1, there is shown the general floor plan of a place of amusement, such, for example, as a dance hall, which hall includes an entrance 1, ticket kiosk 2, turnstiles 3 and passageways 4 and 5 leading to the dance floor 6. The passageways 4 and 5 are formed by a partition 7, which partition extends from the kiosk to a point at the entrance to the dance floor. The partition 7 may be of any suitable height or construction provided it is sufficiently high and otherwise so arranged to prevent persons in one passageway from seeing the person in the other passageway. The partition is provided with a longitudinal slot or opening 8 extending from a point near the outer end thereof through to the inner end of the partition. This slot or opening 8 provides for pairing off couples as the latter pass through the passageways 4 and 5.

Various means may be employed for causing the couples to be paired in such manner that neither partner is aware of the identity of the other. This may be carried out by mounting in the slot or opening 8, a plurality of slidable members 9 which extend into both passageways and are adapted to be taken hold of or in some manner utilized by the persons in the passageways in order

to pair off said persons. Preferably, the members 9 are flexible and have at the ends thereof suitable wrist clamps 10, similar to the ordinary hand-cuff, or if desired, an ordinary ring through which the hands of the persons may be inserted. Preferably the lower side of the slot or opening is notched at predetermined points as at 11, so as to space the members 9 a predetermined distance apart when the latter are arranged for use.

In operation of the apparatus, persons having purchased tickets at the kiosk 2, separate, the men on one side and the ladies 15 on the other, and pass thus separated into the passageways 4 and 5. The selection of the members 9 by the couples is subject to the choice of each person. The persons attach the ring or wrist clamp to them, or in 20 some manner take hold of the members 9, without knowledge of the identity of one another and then proceed through the passageway to the place of amusement, in this instance, the dance floor 6. Upon such passing 25 of the couples, the chains or members 9 will move through the slot 8 and when the couples reach the end of the partition, their identity will be revealed to one another and the couples or partners may then take part 30 in the dancing or other amusement, as the case may be.

In Fig. 1, there is shown a platform 12 such as used for the orchestra, and at some suitable point on the dance floor will be 35 selecting or pairing off apparatus as shown at 13, which apparatus corresponds to the one in the passages 4 and 5. After the couples have finished a dance, they may retire to the apparatus 13 on the dance floor, 40 and cause the members 9 to enter the groove or opening 8 with the men on one side of the partition and the women on the other. Couples thus still paired, either release 45 themselves from the connecting members 9 or an attendant may effect the release, and the members 9 will remain in place in the apparatus 13. The couples then pass out through the passageways provided at the apparatus 13 and enter said passageways 50 again in a diversified order so that different persons will be matched or paired for the next dance or period of amusement.

As shown in Figs. 3 and 4, there may be 55 provided a traveling platform or floor, generally designated 14, which platform or floor may be in the nature of an endless belt 15, traveling over a supporting floor section 16. The persons to be paired will be advanced 60 when stepping on the movable platform or endless belt, thus enhancing the amusement factor. It will be seen that a variety of arrangements may be resorted to as a means for moving the participants throughout the time of pairing them and after such pairing 65 has been effected. Chairs may be mounted

at properly designated points on the apparatus or various other arrangements may be resorted to, it being thought unnecessary to illustrate these arrangements since it is obvious that they may be employed within 70 the scope of the present invention.

Another way in which the apparatus may be employed is for the ticket seller or attendant to give to the participants checks, or tickets having duplicate numbers or symbols, the duplicate checks or tickets being distributed without any regard as to the pairing of the couples except when the latter have entered the passageway or have gained entrance to the place of amusement, such as 80 the dance floor. The holders of the tickets may insert them through the slot or opening in the partition and in this way match the duplicate tickets so as to pair the participants.

The apparatus of the invention is simple as to construction and arrangement, is inexpensive and requires little or no attention or up-keep expense when in use.

The invention provides a method of introducing persons to one another in an interesting and amusing manner, in that the couples or participants are not aware of the identity of one another until they are paired, or the identity may remain unknown until 95 a predetermined time has elapsed following their being paired.

I claim:

1. Amusement apparatus comprising an upright screen member along opposite sides 100 of which persons are adapted to pass in such manner that the persons on one side of the screen are not visible to the persons on the other side and vice versa, members slideable on the screen with portions of the members disposed on opposite sides thereof in order that they may be grasped or in some manner associated with the persons on opposite sides of said screen to designate, without knowledge of the identity of one 110 another, partners for participation in said amusement and means associated with said members for locking said members to the said persons.

2. Amusement apparatus embodying in 115 its construction a screen along opposite sides of which lines of persons are adapted to pass, said screen being constructed so that the persons passing on opposite sides thereof are not visible to one another and having a slot therein opening at one end thereof and members slideable in and removable from the slot with portions disposed on opposite sides of the screen, which members are adapted to be associated with the persons to designate without knowledge of the identity of one another, partners for participation 120 in some form of amusement.

3. Amusement apparatus embodying in 125 its construction a screen along opposite sides

of which lines of persons are adapted to pass, said screen being constructed so that the persons passing on opposite sides thereof are not visible to one another and having a slot therein opening at one end thereof and flexible members slidable in and removable from the slot with portions disposed on opposite sides of the screen, which members are adapted to be associated with the persons to designate without knowledge of the identity of one another, partners for participation in some form of amusement.

4. Amusement apparatus embodying in its construction a screen along opposite sides of which lines of persons are adapted to pass, said screen being constructed so that the persons passing on opposite sides thereof are not visible to one another and having a slot therein opening at one end thereof and flexible members slidable in and removable from the slot with portions disposed on opposite sides of the screen, which members are fixed to the persons to provide for pairing off of partners without knowledge of the identity of the partners until said members have been moved out of said slot.

5. Amusement apparatus comprising an upright screen member along opposite sides

of which persons are adapted to pass in such manner that the persons on one side of the screen are not visible to the persons on the other side and vice versa and members slidable on the screen with portions of the members disposed on opposite sides thereof in order that they may be grasped or in some manner associated with the persons on opposite sides of said screen to designate, without knowledge of the identity of one another, partners for participation in said amusement and a moving support on which the persons are advanced on opposite sides of the screen.

6. Amusement apparatus comprising an upright screen member arranged so that persons located on opposite sides thereof are not visible to one another, flexible members extending through and slidable along the screen with extremities disposed on opposite sides of the screen and means associated with the flexible elements providing for attachment of said elements to persons disposed on opposite sides of the screen, said screen having a slot in which said flexible elements are movable, said slot being unobstructed, open at the ends of the screen and substantially waist high.

JAMES H. PAPPAS.
